GOTTLOB HONOLD, OF STUTTGART, GERMANY, ASSIGNOR TO THE FIRM OF ROBERT BOSCH, OF STUTTGART, GERMANY.

LIGHTING SYSTEM FOR MOVING VEHICLES.

1,193,548.

Specification of Letters Patent.

Patented Aug. 8, 1916.

Application filed June 7, 1915. Serial No. 32,776.

To all whom it may concern:

Be it known that I, GOTTLÖB HONOLD, a subject of the Emperor of Germany, and residing at Stuttgart, Germany, have invented certain new and useful Improvements in Lighting Systems for Moving Vehicles; and I do hereby declare the following to be a full, clear, and exact description of the invention, such as will enable others skilled in the art to which it appertains to make and use the same.

In lighting systems for moving vehicles such as automobiles and motorboats, wherein an automatically regulated generator is driven at varying speed by the engine, it is usual to provide an automatic voltage switch which connects the generator to, and disconnects it from, the circuit of the lamps when the voltage generated thereby has reached a predetermined value, which value is generally equal to that of the storage battery in the system in order to prevent flow of current from the battery to the generator at other times, such as when the vehicle is at rest or is running at low speed. In such systems it is desirable at certain times to disconnect the battery from the system and supply the lamps from the generator alone, and in this case the automatic voltage switch is not only unnecessary, but it is undesirable because it does not allow the generator to supply the lamps at less than full voltage; in other words, it cuts the generator off too soon when the vehicle is slowing down, and cuts it in too late when the speed is rising, the result being that the lamps will be dark at unnecessary times or else the operator must frequently cut in the battery to keep the lights burning.

In accordance with my invention, a switch is provided for connecting the generator alone to the lamps without including the automatic voltage switch in the circuit, and preferably the switch is arranged also to cut in the battery alone or the battery in parallel with the generator and the automatic voltage switch. In this way, the operator has the facility for choosing the source of current supply for the lamps and for cutting the automatic voltage regulator out of circuit when the generator alone is used for lighting purposes.

The accompanying drawing illustrating

the preferred embodiment of my invention, is diagrammatic.

The direct current shunt wound generator *a* is self-regulating or is provided with regulating adjuncts, and it is adapted to be driven by the internal combustion engine on an automobile or motorboat, or in any other suitable way. The generator has one terminal grounded at *x* and the other terminal *c* is connected to the contact *D* of the multi-point rotary switch *s*. The storage battery *e* is likewise grounded and has its other terminal connected with the switch contact *DB* and also with *B* by means of the conductor *g*. The automatic voltage switch may be of any suitable kind, and, as shown, it has a movable core *m* excited by the shunt winding *o*, which is permanently connected across the terminals of the generator. This winding is adjusted to pull up the core *m* until the series contact *k* engages the co-operative stationary contact *n*, when the voltage generated reaches a predetermined value substantially equal to the voltage of the battery and corresponding in some cases to a speed of 600 revolutions per minute of the engine; and the winding is also adjusted to permit the separation of the contacts *k*, *n*, when the voltage of the generator falls to the value at which the battery starts to discharge into the generator. The automatic voltage switch is also provided with a series exciting winding *i* for assuredly holding the contacts *k*, *n* in engagement when current flows from the generator, and also for assuredly bringing about the separation of the contacts *k*, *n* when current flows from the battery to the generator. The series exciting winding *i* is connected to the terminal *c* of the generator and through the co-operative series contacts *k*, *n* and the conductor *p* to the switch contact *db*.

The switch *s* has two radially disposed conducting arms *u* and *v* insulated from each other and supported by the member *w*, which, together with the manually operated handle *z* is fastened on a switch stud. The annular shaped conducting segment *q* is connected by the conductor *t'* to the ammeter *y* and the lamp circuit wire *t* and thence through the lamps *f'*, *f''*, *f'''* to the ground *x*; and the complementary annular shaped conducting segment *r* is connected to *t* by the conductor *t''*.

The switch arm u is arranged to slide along the segment q and successively engage the switch contacts DB, D and B, whereas the contact arm v is arranged to slide along the segment r and engage the switch contact db when the arm u engages DB.

With the foregoing arrangement, the generator and battery may be connected in parallel to the lamps, the automatic voltage switch 10 being in circuit with the generator; or the generator alone may be connected to the lamps without the automatic voltage switch in circuit; or the battery alone may be connected to the lamps. The ammeter y indicates the battery current flowing to the lamps when the battery alone is in circuit, or when it is connected in parallel with the generator, and it also indicates the generator current flowing to the lamps when the generator 15 alone is connected in circuit.

In the position illustrated in the drawing, current from the battery e flows to contact DB, and through the switch arm u , segment q and ammeter y to the lamps f' , f^2 , f^3 by 20 way of the conductors t' and t . The current then flows through the ground connection x to the other terminal of the battery. When the generator a is driven at high enough speed, the shunt exciting coil o closes the 25 series contacts k , n , and current from the generator then flows through the conductor h , series exciting coil i , contacts k , n , conductor p , switch contact db , switch arm v , segment r and conductor t^2 to supply the lamps in 30 parallel with the battery. By turning the switch arm u to contact D, the battery, together with the automatic voltage switch, is cut out of circuit, and the generator alone then supplies the lamps through the ammeter y . Also, by turning the switch arm u to contact 35 B, the generator, together with the automatic voltage switch, are cut out of circuit, and the battery alone then supplies the lamps through the ammeter y . Furthermore, by 40 turning the switch arm to the position indicated by the broken line O—Q, the lamps are cut off from both sources of current supply.

Thus it will be seen that whenever the battery and generator supply the lamps in parallel, the automatic voltage switch is connected in circuit and thereby prevents flow of current from the battery to the generator, which would otherwise occur when the vehicle is at rest or is starting up or slowing 50 down. But when the generator alone supplies the lamps, the automatic voltage switch is cut out of circuit, and therefore the lamps start to burn at a lower speed of the vehicle, 55 and do not go out until the speed of the vehicle is less than would otherwise occur.

Having thus described my invention, what I claim is:

1. In a lighting system for moving vehicles, a generator driven at varying speed,

an automatic voltage switch for the generator, a second source of current, electric lamps, and circuit connections including a switch having one position in which the generator alone is connected to the lamps, 70 and having a second position in which the generator and the automatic switch are connected to the lamps in parallel with the second source of current.

2. In a lighting system for moving vehicles, 75 a generator driven at varying speed, an automatic voltage switch for the generator, a battery, electric lamps, and circuit connections including a switch having one position in which the generator alone is connected to the lamps, and having a second position in which the generator and the automatic switch are connected to the lamps, 80 and also having a third position in which the battery alone is connected to the lamps. 85

3. In a lighting system for moving vehicles, 90 a generator driven at varying speed, an automatic voltage switch for the generator, a battery, electric lamps, and circuit connections including a switch having one position in which the battery alone is connected to the lamps, and having a second position in which the generator alone is connected to the lamps, and also having a third position in which the generator and the automatic switch are connected to the lamps 95 in parallel with the battery.

4. In a lighting system for moving vehicles, 100 a generator driven at varying speed, an automatic voltage switch having a shunt exciting winding connected across the generator terminals and also having co-operative series contacts, a battery, electric lamps, and circuit connections including a switch having one position in which the generator alone is connected to the lamps and also having a second position in which the generator and the series contacts are connected to the lamps in parallel with the battery. 105

5. In a lighting system for moving vehicles, 110 a generator driven at varying speed, an automatic voltage switch for the generator, a battery, electric lamps, and circuit connections including a switch having one position in which the generator is connected to the lamps and also having a second position in which the generator is connected to the lamps in parallel with the battery, said switch having an auxiliary arm arranged 115 to connect the automatic switch in circuit with the generator when the battery and generator are connected in parallel.

6. In a lighting system for moving vehicles, 120 a generator driven at varying speed, an automatic voltage switch for the generator, a battery, electric lamps, and circuit connections including a double-arm multi-point switch having one position in which a one point connected to the battery and a second point connected to the generator 125 130

through the automatic switch are connected in parallel to the lamps through the two arms of the switch, and also having a second position in which a third point connected directly to the generator is connected to the lamps through one arm of the switch.

7. In a lighting system for moving vehicles, a generator driven at varying speed, an automatic voltage switch for the generator, a battery, electric lamps, and circuit connections including a double-arm multi-point switch having one position in which one point connected to the battery and a second point connected to the generator through the automatic switch are connected in parallel to the lamps through the two arms of the switch, and having a second position in which a third point connected directly to the generator is connected to the lamps through one arm of the switch, and also having a third position in which a

fourth point connected to the battery is connected to the lamps through one arm of the switch.

8. In a lighting system for moving vehicles, a generator driven at varying speed, an automatic voltage switch for the generator, a battery, electric lamps, an electric meter, and circuit connections by which the meter is connected in the circuit of the battery alone when the battery alone supplies the lamps and also when the lamps are supplied by the battery and generator in parallel, and also by which the meter is connected in the circuit of the generator when the generator alone supplies the lamps.

In testimony whereof I affix my signature, in presence of two witnesses.

GOTTLOB HONOLD.
